UNITED STATES PATENT OFFICE.

FRANK E. HULETT AND ROBERT E. SHEAL, OF CLEVELAND, OHIO, ASSIGNEES TO THE
WELLMAN-SEAVIER-MORGAN COMPANY, OF CLEVELAND, OHIO.

PONTOON-CRANE.

1,161,679.

Specification of Letters Patent. Patented Nov. 23, 1915.

Application filed June 15, 1914. Serial No. 845,269.

To all whom it may concern:

Be it known that we, FRANK E. HULETT and ROBERT E. SHEAL, of Cleveland, in the county of Cuyahoga and State of Ohio, have 5 invented certain new and useful Improvements in Pontoon-Cranes; and we do hereby declare the following to be a full, clear, and exact description of the invention, such as will enable others skilled in the art to which 10 it appertains to make and use the same.

Our invention relates to an improvement in pontoon cranes.

Pontoon cranes, in use at the present time, are of two types, one known as the bridge 15 type; and the other as the revolving type having a boom with a variable radius. The chief objection to the bridge type is instability in rough waters, and the difficulties of maneuvering it to place it properly in position 20 alongside of a ship, and the chief objections to the rotating type are instability in rough waters; requires a large and unwieldy pontoon; and cannot be used to advantage in making lifts from large boats on 25 account of the limited space on the boats for the rotation of the boom. Again both of these types of pontoon cranes are limited to use in inland and still waters, and it has never been considered safe to take either of 30 these heavy and high cranes to sea in an assembled condition.

The object of this invention is to provide a pontoon crane possessing the advantages of both the bridge and revolving types, without some of the objectionable features of each, and it consists in the parts and combination of parts as will be more fully described and pointed out in the claims.

In the accompanying drawings, Figure 1 40 is a view in side elevation showing the boom retracted; Fig. 2 is a similar view showing the boom projected and also showing the main and auxiliary trolley and hoist ropes or cables, and the mechanism for projecting 45 and retracting the boom; Fig. 3 is an end view; Fig. 4 a diagrammatic view in plan showing the shape of the pontoon and the manner of mooring the same to the side of a vessel, and Fig. 5 is an enlarged view of 50 part of Fig. 2 showing the gearing at the lower end of the boom.

1 represents a pontoon rectangular in shape, and provided at its front end with a curved fender 2, adapted when resting in 55 contact with the side of a vessel, to permit

the pontoon to be swung slightly so as to carry its boom into position over a hatch or particular part of the deck.

As shown in Fig. 4 we provide the pontoon with four capstans 3, located adjacent 60 the four corners, and connect a cable or chain from each to fixed fastenings 4 on the vessel, so that by proper manipulation of the capstans, the pontoon can be swung in either direction, the side of the vessel forming the 65 fulcrum for the pontoon.

5 is the boom the forward portion 6 of which, on which the main trolley travels, is horizontal, and the rear portion 7 thereof is downwardly and rearwardly inclined, and is provided at its rear end with trunnions 8 which latter move in guide ways 9 formed in the sides of the inclined trackway 10, on which the rear end of the boom travels. This trackway is slightly wider than the 75 rear end of the boom so as to receive the latter between its side members, and the latter are provided with the guide ways 9 in which the trunnions 8 travel, the said guideways 9 being closed at their forward ends so as to 80 limit the forward movement of the boom. The trackway 10 is supported on suitable 70 columns or posts 11, properly braced and secured to the pontoon, and it is provided at each side, adjacent the guide ways 9, with 85 the upwardly facing racks 12, which extend throughout the length of the trackway. The trackway 10 is abruptly inclined upwardly from its rear end preferably to slightly less than one half of its length, and is then gradually inclined upwardly to its front end. The trunnions 8, may be, and in this instance are hollow for the shaft 13 shown in Fig. 1, 90 which carries at its outer ends the toothed wheels 14, which are in mesh with the racks, 95 the shaft 13 being actuated by the motor 15 and gearing 16, 17 and 18 carried by and on the boom at the rear end thereof, as shown in Fig. 2.

The boom 6 and 7, is supported in advance of the trackway 10, by the rocking frame 19 which is in the shape of an inverted U, and is journaled at the lower free ends of its side members, as at 20, to suitable supporting members 21 firmly anchored to the 105 pontoon. The boom projects through the rocking frame and is journaled at its opposite sides to the side members of the frame 19, as shown at 22.

The trackway 10, boom 6 and 7, and rock- 110

- ing frame 19, are so constructed and arranged that the top surface of section 6 of the boom, on which the main trolley travels, will remain approximately horizontal both when the boom is projected as in Fig. 2, when it is retracted, as in Fig. 1, and also during its movement from one extreme to the other. When the boom is projected, the rocking frame is inclined forwardly, so that the boom will be held in such position by gravity. In retracting the boom, as soon as the rocking frame 19 passes its vertical center, the weight of the boom will carry the latter to its retracted position. The boom when retracted, is preferably within the outlines of the pontoon, and when retracted is in its lowest position thus lowering the center of gravity and increasing the stability of the pontoon. As the boom is projected, it is also elevated, and when in working position it projects well over the bow of the pontoon and in a position to handle loads on the vessel or other object to which it may be moored.

In the drawings we have shown a main trolley 23 mounted on trackway on the top of horizontal section 6 of the boom, and an auxiliary trolley 24 on a track carried by the lower member of section 6 of the boom. The main trolley is propelled on its trackway in both directions by the main trolley drum 25, and cable 26, which is looped around the drum, and both ends pass forwardly to sheaves 27 located adjacent the journals of the rocking frame 19, and thence up and over sheaves 28, adjacent the journals 22 connecting the boom to the rocking frame, and thence rearwardly around sheaves 29, 30 and 31 and forwardly, one end being secured to the rear end of trolley 23, and the other end passing around sheave 32 at the front end of boom, and thence back and secured to the front end of the trolley. The hoist cables 33 for this trolley, are centrally looped around sheave 34 at the front end of the boom, and then pass over sheaves 35 on the boom, and sheaves 36 on the trolley, down and under sheaves on the main hoist block 37, up and over sheaves 38 on the trolley, down and under sheaves on the block 37 and thence up and over rear sheaves 38^a on the trolley. From thence they pass rearwardly around sheaves 39, 40, 41 and 42 down and around sheaves 43 adjacent the journals of the rocking frame, and thence back to the main hoist drum 44 to which they are secured in the usual manner.

The cable 45 for the traverse of the auxiliary trolley 24, is connected at one end to the forward end of said trolley, and passes forwardly and around sheave 46 at the front end of the boom and from thence rearwardly around sheave 47, down and around the drum 48, up over another sheave 47 and forwardly to the rear end of the trolley to

which it is secured. The drum 48 which is mounted on section 7 of the boom is driven by the motor 49 and gearing 50 and 51, also carried by the boom.

The hoist rope 52, for the auxiliary trolley 70 24 is secured at its front end to the boom at 53 and passes rearwardly over a sheave on the trolley, down and under a sheave in the hoist block 54; up and over a sheave on the trolley; down and under a sheave in the 75 hoist block, up and over a rear sheave on the trolley, and thence rearwardly over sheave 55 and down to hoist drum 56 which is actuated by a motor 57 and suitable gearing, the said motor, drum and gearing being 80 carried on the boom. With this construction it will be seen that the boom can be moved from one position to the other without affecting the several cables.

While we have shown and described mechanism for actuating the boom, and also mechanism for the several trolleys, we would have it distinctly understood that we do not confine ourselves to such details, as our present invention relates broadly to the manner of mounting the boom on a pontoon, and not to the mechanism for actuating the boom or the hoist mechanism. 85 90

With a crane as above described the boom may be retracted within the outlines of the pontoon, thereby accomplishing two important results, to wit,—lowering itself toward the deck of the pontoon thereby rendering the structure as a whole more stable against wind and waves, and permitting the crane to approach the work without interfering projections. When in its lowered position it is automatically held fast in such position and is capable of being towed to sea in its assembled position, and is available for moving around inland harbors and bays from one location to another. It can be brought alongside a ship or dock with no projections extending beyond the limits of the pontoon itself, and when in position its boom can be projected from the pontoon between masts or other projection by a longitudinal movement. By rounding the end of the pontoon and the arrangement of capstans as shown, the pontoon can be slightly rotated relatively to the work on which it is engaged, and thus avail itself of the advantage of the rotating type of crane in placing and displacing work.

Another advantage of the type of crane is 120
that the loads are all taken care of by simple
beams and struts, which permits of lighter
and simpler construction and is entirely one-
ended, the machinery all being located on 125
the opposite end from the loads handled,
and assisting materially in balancing the
float, the other or front end of the deck be-
ing free or available for depositing the
loads.

In the present instance we have shown 130

the machinery and boiler house at the extreme rear end, and the cage 58 for the operator in an elevated position at the front end of the trackway 10.

5 It is evident that numerous changes and modifications might be made without departing from the spirit of our invention, hence we would have it understood that we do not confine ourselves to the details but 10 consider ourselves at liberty to make radical departure therefrom.

Having fully described our invention what we claim as new and desire to secure by Letters-Patent, is:—

15 1. The combination of a pontoon, means on said pontoon for supporting one end of a boom, a boom having sliding engagement with said supporting means, and means for raising and lowering the boom and for moving it longitudinally, whereby the boom will project over one end of the pontoon when in its raised position and will be withdrawn to a position over the pontoon when in its lowered position.

25 2. The combination of a pontoon, a boom mounted for longitudinal and vertical movement thereon, and means for shifting the boom to its elevated and projected position and for retracting it to its lowered position over the deck of the pontoon.

35 3. The combination of a pontoon, a boom having a sliding connection with the pontoon whereby it may be moved longitudinally and means for elevating one end of said boom and projecting it over one end of the pontoon, and for lowering it and retracting it to a position over the pontoon.

40 4. The combination of a pontoon, a fixed support and a rocking support thereon, a boom having sliding connection with the fixed support and a pivotal connection with a rocking support, and means for shifting the boom to elevated and projected position and for retracting it to its lowered position over the deck of the pontoon.

45 5. The combination of a pontoon, an inclined support, a rocking support in advance of the inclined support, a boom having a sliding connection with the inclined support and a pivotal connection with said rocking support, and means for elevating and projecting the boom and for lowering and retracting the same.

55 6. The combination of a pontoon, a boom movable longitudinally thereon, an inclined support with which the boom has a sliding connection, a rocking support for the boom at the front, means for moving the boom longitudinally whereby it will be elevated when projected and lowered when withdrawn onto the pontoon, a trolley mounted to travel on said boom, and means for actuating the trolley.

65 7. The combination of a pontoon, a boom movable longitudinally thereon so as to pro-

ject at one end, an inclined support for the rear end of the boom, a rocking support for the boom in advance of the inclined support, means engaging the rear end of the boom for moving it longitudinally, a trolley 70 mounted to travel on said boom, and means for actuating the trolley.

8. The combination of a longitudinally movable boom the rear end of which projects downwardly, a rocking support for the 75 boom in advance of its depending rear portion and a fixed support with which the lower end of said depending portion has sliding connection.

9. The combination of a longitudinally 80 movable boom, a rocking support for same intermediate its ends, a fixed support for its rear end, the said boom having sliding connection with said fixed support, a trolley mounted to travel on said boom and means 85 for actuating the trolley.

10. The combination of a longitudinally and vertically movable boom, a fixed support with which one end of the boom has a 90 sliding connection, a rocking support for the other end, whereby when the boom is moved longitudinally it will be raised or lowered, a trolley mounted to move on said boom, and a motor and gearing on the boom 95 for actuating the trolley.

11. The combination of a longitudinally movable non-rotating boom, a fixed support with which one end of the boom has a sliding connection, a rocking support for the other end whereby when the boom is moved 100 longitudinally it will be raised or lowered, a trolley mounted to travel on the boom and carrying a hoist block and motors and gearing carried by the boom for actuating the trolley and hoist cables. 105

12. The combination of a support, a boom having a sliding connection therewith whereby it may move longitudinally, a rocking support for the boom intermediate the ends of the latter, a motor carried by the 110 boom and means actuated by the said motor for sliding the boom longitudinally on its support.

13. The combination of an inclined support, a boom having a sliding connection at 115 its rear end with said support, a rocking support for the boom in advance of said inclined support and a motor carried by said boom and means actuated by the motor and engaging means carried by the said inclined support for moving the boom longitudinally. 120

14. The combination of an inclined support having a rack thereon, a boom having a sliding connection at its rear end with said support, a toothed wheel carried by the 125 boom and meshing with the rack, a motor also carried by the boom for rotating the toothed wheel and a rocking support for the outer portion of the boom.

15. The combination of an inclined sup- 130

port having a rack thereon, a boom having a sliding connection at its rear end with said support, a rocking support for the boom intermediate the ends of the latter, a toothed wheel carried by the boom adjacent the rear end of the latter and meshing with the rack, and a motor on the boom for actuating said toothed wheel.

16. The combination of a longitudinally movable boom having a sliding connection with a support at its rear end, and a rocking support for said boom intermediate its ends, the said rocking support normally

standing at one side of a vertical plane when the boom is projected and at the other 15 side of said plane when the boom is retracted so that the boom is retained in its two positions by gravity.

In testimony whereof, we have signed this specification in the presence of two subscribing witnesses.

FRANK E. HULETT.
